(57) **CLAIM**

The ornamental design for a biomedical instrument, substantially as shown and described.

DESCRIPTION

FIG. 1 shows an isometric view of the biomedical instrument incorporating my design.

FIG. 2 is a front view thereof;

FIG. 3 is a side view thereof;

FIG. 4 is a back view thereof;

FIG. 5 is a top view thereof;

FIG. 6 is a bottom view thereof;

FIG. 7 is a side view of the biomedical instrument with the fluid vials in an open, accessible position;

FIG. 8 is a side view of the biomedical instrument with the sample loading door in an open, accessible position; and,

FIG. 9 is an isometric view of the biomedical instrument with the sample loading door in an open, accessible position.

A design for a biomedical instrument is shown in FIGS. 1-9. The broken lines in the drawings are included for the purpose of illustrating portions of the biomedical instrument that form no part of the claimed design.
